KNEE PROTECTOR

Lola M. Patterson, New Bremen, Ohio

Application January 26, 1945, Serial No. 574,699

6 Claims. (Cl. 2—24)

1

This invention relates to covers or protectors intended primarily for protection of portions of the body particularly subject to injury, such as the knee or elbow.

It is an object of my invention to provide a pad or protector that may be easily and quickly attached to and detached from the knee or elbow.

Another object is to provide a pad which, when properly positioned upon the knee or elbow, is securely held in place, while providing effective protection.

A further object is to provide a pad that is moisture-proof, durable, that may be worn without discomfort, that is neat and pleasing in appearance, and, most important of all, that fully protects the knee or elbow against injury and disorders such as housemaid's knee, common among those who do a great deal of work upon their knees.

Further objects and advantages will become apparent as the description proceeds.

In the drawings:

Figure 1 is a perspective view of one of my pads attached to the knee of a user.

Figure 2 is a perspective view of a pad constructed according to my invention and showing particularly the protecting pad, the attached flap and the attaching strips.

Figure 3 is a side elevation of the pad shown at Figure 2.

Figure 4 is a view of a modified form in which the pad is curved in one dimension to conform to the configuration of the limb.

Figure 5 is a view showing the protective pad in use as when kneeling.

Figure 6 is a perspective view of a modification wherein the outer covering or casing forms a pocket or compartment wherein resilient or other soft protecting materials such as sponge rubber or "kapok," may be inserted and retained, which materials may, at the same time be easily removed for replacement or cleaning.

In the drawing, wherein like numerals identify corresponding parts throughout, A identifies the legs of a user and to which my protecting pad has been attached. This pad consists, in general, of a main section or cushion 10 of a width sufficient to extend a substantial distance over and about the knee or elbow, and of a length sufficient to provide a portion 10a fully covering and protecting the knee or elbow and, at the same time, providing a supporting and attaching flap 10b. Preferably, but not necessary, section 10 may consist of fabric impregnated with rubber or other material so as to be waterproof and insectproof while at the same time highly resistant to wear.

2

If desired, a layer of material especially resistant to wear, may be attached in any desired manner to the outer surface of portion 10a.

5 A pad 11 of soft, resilient protective material is attached to one side of portion 10a and may consist of side sections 11a and a bottom section 11b firmly bound and secured to the portion 10a of main section 10 as by sewing.

A body-attaching strip of material 12 has its ends attached to opposite sides of pad 11 adjacent the outer end thereof, while a second strip of material 13 has its ends secured to the side edges of flap or portion 10b adjacent the free end thereof. These strips are preferably of elastic material and are of a length such that, combined with the width of the sections to which they are attached, they form loops adapted to encircle and snugly fit the adjacent limb of the wearer. If desired, these strips may be made adjustable as by the use of clasps or buckles.

20 Figure 4 shows a modification wherein two opposed end section 11a are curved whereby the pad is arcuate in a plane transverse to and snugly fits the limb of the user. In other respects the construction is the same as in the species of Figures 1 to 3.

Figure 5 shows the pad in the position it assumes when the user is kneeling and it will be noted that, in such position flap 10b extends well up beyond the joint and not only aids in preventing moisture and dirt from entering between the pad and limb of the user, but also retains the pad in position by causing the retaining strap 13 to be positioned well up on the limb.

At Figure 6 I have shown a modification in which the parts are generally of the same shape and configuration as in the species of Figures 1 to 4, inclusive, and thus have been given corresponding numerals as in Figures 1 to 4. However, one end section 11a, of Figures 1 to 4, is replaced by a flap or section 14 secured along one edge to main section 10 and of a width sufficient to overlap bottom section 11b as indicated at 14a. This overlapping portion is secured to bottom section 11b by any suitable means such as snap fasteners 15 or any other releasable fastener such as a zipper, to thereby form a chamber or pocket within which may be fitted a pad of resilient material such as sponge rubber. By this arrangement, the flap may be opened to remove the pad of resilient material therein whereby the disassembled parts may be readily cleaned and either part may be replaced without replacement of the other.

55 The use and operation of my pad will be obvious from the foregoing description. It will be noted

that the section 10b extends to a point remote from the joint portion of the user and not only aids in affording protection against the entrance of moisture between the protector and the covered body area, but also greatly adds to the comfort of the wearer, since the elastic flap 13 is thereby prevented from displacement into the crease formed by doubling or flexing of the protected joint, whereby the pad does not move or "creep" upon flexure of the joint.

The same features are present in the species of Figure 6, with the added advantages that the pocket formed by the portions 10a, 11a, 11b and flap 14, may be opened to remove the pad or filling of sponge rubber or other resilient material contained therein, after which the fabric portions may be easily cleaned or laundered. Furthermore, the pad may be transferred and used repeatedly after the fabric or covering parts have worn out.

It will be understood that my protector will ordinarily be sold and used in pairs and that they will be especially useful for maids, gardeners, garage men and others who do a considerable amount of work in a kneeling position. Not only do they protect those portions of the limb otherwise exposed to injury, but they also protect the hosiery against wear and tear and greatly lengthen its life.

While I have selected a preferred form of my invention for illustration, it is to be understood that I reserve all such modifications, alterations and substitutions as fall within the scope of the subjoined claims.

Having now described the invention, what I claim and desire to secure by Letters Patent is:

1. In a pad for protecting the body, an elongated strip of material having end edges, sections of material secured to said strip to form a pocket over substantially one-half the area of said strip, said pocket being completely closed by said material, protective padding within said pocket, and elastic straps secured to said pad adjacent the said end edges of said strip.

2. In a protective pad, an elongated main section of flexible material, end and side edges of material secured to said main section and extending over approximately one half the area of said main section to form a pocket completely closed on all sides except one and adapted to receive a pad of cushioning material, a flap secured to said main section and completely closing the open side of said pocket, means permanently attaching the free end of said flap to the side section of said pocket, and elastic band means secured to the remote ends of said main section and pocket, respectively.

3. In a protective pad, side and end sections of flexible material having their edges perma-

nently secured together to form a pocket, one side of which is open, a flap permanently attached along one edge to an edge of a first section adjacent said open side, means adapted permanently to secure the opposite edge of said flap to the section opposite said first section in order completely to close said pocket, a pad of resilient material in said pocket, a second flap having an edge secured to said edge of said first section, body-attaching strap means secured to said pocket sections at the end thereof remote from said second flap, and body-attaching strap means secured to said second flap at its end remote from said pocket.

15 4. In a protective pad, an elongated main section of flexible material, end and side edges of material secured to said main section and extending over approximately one-half the area of said main section to form a pocket, a body of material permanently secured to said end and side edges to completely close the pocket, cushioning material in said completely closed pocket and elastic band means secured to the remote ends of said main section and pocket respectively.

5. In a protective pad, an elongated main section of flexible material, end and side members of the same material permanently secured to said main section and extending transversely thereof to form a pocket, a cover for the pocket permanently secured to said end and side members, said cover being made of the same material as the main section and the end and side members and serving completely to close the pocket, cushioning material within said pocket and elastic band means secured to the remote ends of said main section and pocket respectively.

40 6. In a protective pad, an elongated main section of flexible material to which is sewed end, side and top portions of flexible material extending over approximately one-half of the area of said main section to form a completely closed pocket, cushioning material in said pocket, an elastic band means secured to said main section and pocket respectively.

LOLA M. PATTERSON.
